UNITED STATES PATENT OFFICE.

REINHOLD SZELINSKI, OF RIETBERG, GERMANY.

AUTOMATIC RAILWAY COUPLING.

Application filed June 20, 1927, Serial No. 200,255, and in Germany December 7, 1926.

Laterally operated railway couplings comprising a heart-shaped double coupling hook and a slide longitudinally adjustable on the draw-bar of the hook and carrying 5 the pivotal coupling eyes, are already known.

According to the invention, the ends of 10 said coupling eyes are extended beyond their pivots while coil springs are attached to said extensions for keeping the eyes in 15 closed position, while furthermore longitudinally guided and slidable keys are provided for either closing or opening the coupling eyes, and finally a fixed parallel 20 guide is provided for the coupling eyes for closing or folding the same in their uncoupled position.

The accompanying drawing illustrates the 25 improved arrangement: Fig. 1 is a longitudinal section on the line A—B of Fig. 2, which is a plan view of the improved railway coupling as mounted on the end of a railway car, Figs. 3, 4 and 5 are longitudinal sections respectively on the lines C—D, E—F, 30 and G—H, of Fig. 2, Fig. 6 is a perspective view of a detail of the improved railway coupling on a larger scale, while Figs. 7, 35 8 and 9 show in diagrammatical side views the different steps of coupling.

The draw-bar *a* carries at its end beyond 40 the end wall of the car the heart-shaped double coupling hook *b* and on the inner side of said end wall a slide *c*, that can be moved thereon in longitudinal direction by 45 means of a screw-spindle *d* engaging with the lower end of said slide. Said screw-spindle can be operated by means of a bevel gear *e* from a transverse spindle *w* projecting beyond the sides of the railway car and carrying there crank handles *f*. Said slide *c* carries two coupling eyes *k* and *i* pivoted 50 thereto at *g* and *h* and at their ends extended beyond their pivots, on which extensions lateral pins *l*, *m* are provided, to which coil 55 springs *n*, *o* are attached for keeping the eyes in closed position (Figs. 2, 5 and 6). The two longitudinal members *t* of the underframing of the car carry longitudinally guided and slidable keys *q* (Figs. 2, 3, 4) 60 by which said pins *l*, *m* (Fig. 6) are so guided that the coupling eyes *k*, *i* are opened by a displacement of the keys *q* toward the end of the car and closed by moving said

keys in opposite direction. Said displacement of the keys *q* takes place by means of 55 a system of levers *s*, *u*, *x*, *y*, *z* (Fig. 3) adapted to be operated from the sides of the car by means of hand cranks *r*. Besides, on the members *t* (Fig. 4) a parallel 60 guide *p* is fixed for folding the coupling eyes in their uncoupled position and arrest the same in the middle recess of the coupling hook *b* (Fig. 7, left-hand hook).

To couple two cars, it is only necessary 65 to operate one of the two couplings. First, before running the two cars upon one another, by means of the hand cranks *f* and slide *c* the two eyes *k*, *i* are partly opened (Fig. 7, right-hand hook). Upon the cars 70 being run upon one another, the partly opened coupling eyes *k*, *i* of one car are moved over the heart-shaped coupling hook *b* of the other car until they engage in the upper and lower mouths thereof by action 75 of the coil springs *n*, *o* (Figs. 6 and 8). To secure the coupling in its locked position, the slide *c* is retracted so that the coupling eyes cannot move out of the hook (Fig. 9). The uncoupling is effected by an operation 80 of the parts in reverse direction, the keys *q* operated by the hand cranks *r* serving then to lift the coupling eyes out of the hook. Preferably, said hand cranks can be locked in any position.

What I claim, is:—

1. In an automatic railway coupling, the combination of a draw-bar, a heart-shaped double coupling hook, a slide on said draw-bar adapted to be adjusted thereon in longitudinal direction, pivotal coupling eyes on 90 said slide having their ends extended beyond their pivots, and coil springs attached to said latter extensions and acting to keep said eyes in closed position.

2. In a railway coupling as specified in 95 claim 1, longitudinally guided and slidable keys for either opening or closing said coupling eyes.

3. In a railway coupling as specified in 100 claim 1, a fixed parallel guide for said coupling eyes for closing the same in their uncoupled position.

In testimony whereof I have hereunto set my hand.

REINHOLD SZELINSKI.
